CLAIM

The ornamental design for a sheet product dispenser, as shown and described.

DESCRIPTION

FIG. 1 is a perspective view of the sheet product dispenser, the sheet product dispenser including broken lines, which are used in the present drawing and throughout the drawings to represent environment and which form no part of the claimed invention;

FIG. 2 is a front view of the sheet product dispenser;

FIG. 3 is a rear view of the sheet product dispenser;

FIG. 4 is a left side view of the sheet product dispenser;

FIG. 5 is a right side view of the sheet product dispenser;

FIG. 6 is a top plan view of the sheet product dispenser; and,

FIG. 7 is a bottom plan view of the sheet product dispenser.
